LOCOMOTIVE TENDER

Francis Hogg, Wesleyville, Pa., assignor to The Standard Stoker Company, Incorporated, a corporation of Delaware

Application November 13, 1931, Serial No. 574,778

7 Claims. (Cl. 105—232)

This invention relates to locomotive tenders with means for moving the coal forwardly in the tender bin from the rear of the bin to the front, placing it within convenient reach of the fireman for delivering it to the locomotive firebox.

It is an object of the invention to provide a novel, simple, economical and efficient means for effecting the transfer of fuel from the rearward to the forward end of the fuel bin of a locomotive tender.

It is a further object of the invention to provide a novel tender arrangement wherein all the driving mechanism for the coal passer is conveniently located for purposes of installation, repair and inspection.

Other and further objects and advantages of the invention reside in the combination of elements and in the structure as hereinafter described and as illustrated in the accompanying drawings, in which

Fig. 1 is a central, longitudinal vertical section of the forward portion of a locomotive tender and the rearward portion of a locomotive with the invention applied thereto, parts being shown in elevation;

Fig. 2 is a section on the line 2—2 of Fig. 1 with parts removed;

Fig. 3 is a detail section on the line 3—3 of Fig. 2;

Fig. 4 is a section on the line 4—4 of Fig. 3 with portions of the tender shown in section;

Fig. 5 is a detail of a portion of the endless conveyor with parts broken away; and

Fig. 6 is a longitudinal vertical section through a portion of the tender illustrating a modified form of driving arrangement.

In the drawings, referring more particularly to the preferred form illustrated in Figures 1 to 5 inclusive, a locomotive is indicated generally by the numeral 10 and the tender therefor is shown at 11. The locomotive comprises the conventional cab deck 12, firebox 13 having a backwall 14 with an opening 15 therethrough, and the grates 16. The tender comprises the fuel bin 17 and the water compartment 18 separated by the rear slope sheet 19, side slope sheets 20 and 21 and the bin bottom wall 22.

Extending longitudinally of the fuel bin 17 and mounted on the bin bottom wall 22 is a longitudinal endless feed conveyor 23 forming a movable floor for the fuel bin 17. This endless conveyor embodies a plurality of transverse L-shaped members 24 and welded in the opposite ends of the L-shaped members 24 are the lugs 25. The lugs 25 are tapped and threaded to receive the

threaded portion 26 of the bolts 27. A plurality of links 28 forming a chain 29 engage the unthreaded portion 30 of the bolts 27 tying the L-shaped members 24 together.

The endless conveyor 23 travels about the toothed wheels 31, the links 28 fitting between the teeth 32 of the wheels 31. The wheels 31 are secured to the transverse shaft 33 by means of the keys 35, the shaft 33 being journaled in bearings as 36 which are fixed to the tender inner walls 37. At its rearward end the endless conveyor 23 is supported from the transverse shaft 34.

At the forward end of the tender and opening through its front wall is formed a compartment 38 arranged to receive part or all of the driving mechanism for the endless conveyor 23. The compartment 38 is located at one side of the endless conveyor 23, the upper portion thereof extending into one of the bunkers 39 and the lower portion extending into the water compartment 18.

An extension 40 of the shaft 33 penetrates into the compartment 38 and has a sprocket 41 mounted thereon. A smaller sprocket 42 its ratio to the larger sprocket 41 being such as to produce the desired speed reduction, is mounted on a transversely extending shaft 43 journaled in bearings 44 fixed to the sides of the compartment 38 and is connected with the sprocket 41 by a driving chain 45.

A longitudinal shaft 46 is mounted in the compartment 38, extending forwardly through its open forward end, and mounted on its rearward end is a bevel gear 47 engaging the bevel gear 48 mounted on the shaft 43. A motor 49 for driving the endless conveyor 23 is preferably mounted from the underside of the locomotive cab deck 12 and its power shaft 50 is universally connected with the shaft 46 through the extensible shaft 51.

In order to prevent sagging of the upper turn of the endless conveyor 23 and to prevent fuel particles from lodging between the upper and lower turns, a plate 52 is provided directly beneath the upper turn and is securely attached to the tender inner walls 37. Supported from the plate 52 are the bearings 53 and 54 for the shafts 45 and 33 and 40 respectively.

The bin bottom wall 22 is provided with a wear plate 55 extending laterally from one to the other of the tender inner walls 37. The rearward end of the plate 55 curves upwardly following the periphery of the endless conveyor and is attached to the rear slope sheet 19 forming a seal for preventing fuel from lodging behind the endless conveyor. The forward end of the plate 55 curves upwardly following the periphery of the

- endless conveyor, then slopes downwardly and forwardly and extends horizontally forward forming a shovelling platform 56 upon which the fuel is delivered by the endless conveyor.
- 5 The sloping rearwall of the shovelling platform 56 permits greater ease in filling the shovel with coal and prevents the coal from being pushed back in contact with the endless conveyor.
- 10 A coalgate 57 is arranged between the bunkers 39 immediately in front of the endless conveyor 23. A space 58 is permitted to remain between the bottom of the coalgate 57 and the endless conveyor 23, through which coal falls onto the shovelling platform 56. When the bin is full, 15 coal will of itself fall by gravity through the space 58, and when the supply of coal decreases to such an extent that it no longer falls through the space 58 by gravity then the endless conveyor 23 is put in operation to deliver the coal 20 through the space 58.
- 15 In Figure 6 is shown a modified form of driving arrangement. The motor M is shown mounted in the compartment 38, arranged to reciprocate the piston rod 60 in the piston rod 25 guide 61. A lever 62 having arms 63 and 64 is pivotally mounted on the shaft 43. The arm 63 is provided with a slot 65 receiving the pin 66 of the piston rod 60. The arm 64 is provided with a toothed member 67 arranged to engage the serrated wheel 68 which is rigidly fixed to the shaft 43. Thus when the piston 30 68 is moved towards the right, the toothed member 67 engages the serrated edge of the wheel 68 moving it in a counter clockwise direction. The movement of 35 the wheel 68 is communicated to the shaft 43 in turn moving the driving chain 45 which drives the endless conveyor 23 through the shaft 40. When the piston 60 is moved towards the left, the toothed member 67 is moved in a clockwise 40 direction disengaging it from the serrated wheel 68 permitting it to ride over the serrations to a position where it may again be moved in a counter clockwise direction moving the serrated wheel 68 on the return stroke of the piston rod 60.
- 45 The preferred form of the invention is arranged to be operated continuously and uninterruptedly while the modified form operates continuously but interruptedly since motion in the latter form is transmitted to the endless conveyor on only one stroke of the piston rod 60. The endless conveyor of either the preferred or 50 the modified form of the invention is however, operated only at such intervals when the coal no longer of itself falls through the opening between the front of the endless conveyor and the coal gate and when it is desired to add coal to the fire in the locomotive firebox.
- 55 I claim:
1. In a locomotive tender having a fuel bin, a shovelling platform and a water compartment, a coal passer mounted in said bin wholly above the plane of said shovelling platform, a water tight compartment extending below the plane of said shovelling platform at the forward end of the tender in said water compartment, said water tight compartment opening through an exterior wall of the tender, and drive mechanism for said coal passer in said water tight compartment.
2. In a locomotive tender having a fuel bin, a shovelling platform and a water compartment
- back of and extending under the bin, an endless conveyor mounted in said bin for moving the fuel to the forward end of the bin, said endless conveyor being disposed wholly above the plane of said shovelling platform, a water tight compartment at the forward end of the tender in said water compartment extending below the plane of said shovelling platform, said water tight compartment opening through an exterior wall of the tender and drive mechanism for said conveyor in said water tight compartment.
3. In a locomotive tender having a fuel bin with a floor and a water compartment back of and extending under the bin, an endless conveyor mounted in said bin for moving the fuel to the forward end of the bin, a water tight compartment at the forward end of the tender in said water compartment, drive mechanism for said conveyor in said water tight compartment, and a wear plate for said fuel bin floor extending 10 forwardly beyond the forward end of said conveyor, said extension forming a shovelling platform.
4. A locomotive tender having a fuel bin provided with a rear slope sheet, side slope sheets 15 and a shovelling platform, an endless conveyor mounted horizontally wholly above said shovelling platform and beneath the lower marginal edges of said slope sheets forming a movable fuel carrying floor for said bin.
5. A locomotive tender having rear and side slope sheets forming side walls of a fuel bin, an endless conveyor subjacent the lower edges of said rear and side slope sheets forming a movable fuel carrying floor for the opening defined by the lower marginal edges of said rear and side slope sheets and a shovelling platform at the forward end of the tender below the level of the fuel carrying surface of said conveyor receiving all of the fuel advanced by said conveyor.
6. A locomotive tender having rear and side slope sheets forming side walls of a fuel bin, an endless conveyor subjacent the lower edges of said rear and side slope sheets forming a movable fuel carrying floor for the opening defined by the lower marginal edges of said rear and side slope sheets, a shovelling platform forward of and below the level of the fuel carrying surface of said conveyor for receiving fuel therefrom by gravity and a coal gate mounted over and spaced above said shovelling platform forward of said conveyor forming an opening permitting the fuel to drop by gravity from the front end of the bin onto the shovelling platform.
7. A locomotive tender having rear and side slope sheets forming side walls of a fuel bin, a horizontally disposed endless conveyor subjacent the lower edges of said rear and side slope sheets forming a movable fuel carrying floor for the opening defined by the lower marginal edges of said rear and side slope sheets, a shovelling platform positioned forward of said conveyor in a horizontal plane below the plane of the fuel carrying surface of the conveyor and receiving fuel therefrom and a coal gate mounted over and spaced above said shovelling platform forward of said conveyor forming an opening permitting the fuel to drop by gravity from the front end of the bin onto the shovelling platform.
